Claims priority, application Germany June 20, 1952

8 Claims. (Cl. 112—210)

This invention relates to certain improvements in sewing machines and has special reference to a device for changing over from forward sewing to reverse sewing and for semi-automatic locking of a seam sewn by the machine.

It is an object of the present invention to provide means for facilitating the operation of such a device and for ensuring a reliable operation thereof.

In a sewing machine according to the present invention the change-over between forward sewing and reverse sewing is effected by means of an electromagnet acting upon the stitch-setting means. This electromagnet may be energized under the control of a member which can be operated at will, for example a lever to be operated by the seamstress with her knee. Changes between forward and reverse sewing can then be effected quickly, conveniently and in operationally reliable manner by contact closure without the seamstress having, as hitherto, to operate by hand the stitch-setting means usually provided on the superstructure of the machine. Consequently, even for these changes, she can leave her hands on the material being sewn by the machine and can thus ensure accurate guidance of the said material.

This device proves particularly advantageous in the locking of a seam sewn by the machine. This operation is performed by sewing a certain number of stitches, for example four stitches, in a forward direction and then the same number of stitches in a reverse direction.

For the purpose of semi-automatic locking of the seam a control device which acts upon an auxiliary drive, imparting to the sewing machine a speed lower than that derived from the normal main drive means is controlled by a switch device by which the circuit of the control device can be closed or opened at will for the duration of more than one revolution of the machine shaft. The means for effecting the reverse sewing is also rendered operative by an electromagnet included in the circuit of the control device. Thus, the circuit of a control device is controlled by a contact device in such a way, after the main drive has been disconnected, that this control device continues to impart rotary motion to the machine shaft, at a substantially reduced speed, as far as a desired dead-centre position of the needle of the sewing machine. This contact device also causes the reverse sewing of the sewing machine.

In accordance with the operation of this invention the knee lever of the contact device is actuated a distance of one notch of a ratchet wheel during operation of the sewing machine. The sewing machine continues to stitch with suitably reduced, but constant, speed as long as a predetermined pressure is exerted upon the knee lever of the contact device. When the desired number of stitches have been sewn, the contact device is actuated to a further notch of the ratchet wheel by means of the knee lever. In this latter position the control device is inactive for a short time while the contact device changes over the sewing machine to reverse sewing. If the contact device is again advanced through one step, i. e., to

2

the next detent of the ratchet wheel, the sewing machine will sew in a reverse direction at a suitably reduced but constant speed. This type of actuation of the contact device can be repeated as often as desired. If the material being sewn is in a position requiring reverse sewing for locking the seam, the main drive is disengaged in such a way that a few stitches can still be sewn with the control device. To accomplish this reverse sewing, the contact device has to be moved to the first detent of the ratchet wheel. If now the knee lever is set to the second detent of the ratchet wheel, it is possible to lock the seam in the manner described above.

In the above described device it is necessary to exert permanent control pressure upon the lever engaged in the respective notch. In case of a reduction of the control pressure exerted on the contact device the controller cylinder would return to its initial position, whereby the cycle of operations would be interrupted.

It is an important object of the present invention to provide additional means rendering it unnecessary to exert such permanent control pressure.

With this special object in mind, the contact device according to the present invention is constructed in such a way that the control pressure is exerted upon a ratchet wheel, through a pawl which is connected with the knee lever of the contact device. The ratchet wheel is directly connected with a toothed wheel which drives a controller cylinder at a suitable predetermined reduced speed. The controller cylinder is constructed in such a way that it is automatically stopped by the pressure of the contact springs in each of the contact and zero positions of the controller cylinder. On the other hand the pitch of the ratchet wheel according to the invention is adapted in such a way that the pawl is able to engage the succeeding tooth of the ratchet wheel only when the required number of contact positions of the controller cylinder has been passed and the controller cylinder is again in its zero position. A return spring on the pawl moves the control lever into an end position if no control pressure is exerted. However, a new cycle of switching operations can be initiated only when, as described above, all switch positions of the first cycle of contacts have been passed.

According to a further feature of the present invention the contact shaft is operating on the free wheel principle. If no control pressure is exerted, the contact shaft need not return to its initial position, but it can remain in its position until a new control pressure is exerted.

Other and further objects, features and advantages of the invention will be pointed out hereinafter and appear in the appended claims forming part of the application.

In the accompanying drawings a now preferred embodiment of the invention is shown by way of illustration and not by way of limitation.

Fig. 1 is a longitudinal section on line I—I of Fig. 3,
 Fig. 2 is a section on line II—II of Fig. 1,
 Fig. 3 is a section on line III—III of Fig. 1,
 Fig. 4 is a section on line IV—IV of Fig. 1,
 Fig. 5 is a side view of the controller cylinder with the current carrying contacts,

Fig. 6 is a development of the controller cylinder, the position of the current carrying contacts corresponding to the position A of the control lever,

Fig. 7 is a diagrammatic view of the contact device with its control lever and the circuit diagram, including the circuit for an electromagnet and the circuit for the control device, the controller cylinder in this case being in the position A,

Fig. 8 is a diagrammatic view similar to Fig. 7, but showing the controller cylinder only, in the position B,

Fig. 9 is a diagrammatic view of the controller cylinder in the position C,

Fig. 10 is a diagrammatic view of the controller cylinder in the position D, and

Fig. 11 is a diagrammatic view of the controller cylinder in the position E which corresponds to position A.

Fig. 12 illustrates one embodiment of the present invention as applied to a sewing machine.

Fig. 13 is a left end view of the structure illustrated in Fig. 12, and

Fig. 14 is an enlarged sectional view of the stitch setting screw shown in Figs. 12 and 13 taken along the line 14-14 in Fig. 12.

Similar reference numerals denote similar parts in the different views.

Referring now to the drawings in greater detail, it will be seen that the contact device for semi-automatic locking of the seam comprises a shaft 2 which is fixedly arranged in a casing or frame 1. Shaft 2 may be threaded at one end thereof to receive a bolt 3 for clamping shaft 2 to frame 1. Rotatably mounted on the shaft 2 is a body of insulating material preferably consisting of two parts 4, 5 and being arrested in an axial direction by means of a setting ring 6 and a worm screw 7. The insulating body is formed with flanges 8 and 9 in whose circular recesses are inserted contact pins 10, 11, 12, 13, 14 and 15. Provided on the circumference of the insulating body 4 are cams 16, 17, 18, 19, 20, and 21 which are shaped in such a way as to engage into a depression of a correspondingly shaped contact springs 22, 23, Fig. 2. In an analogous way the insulating body 5 is formed with circularly shaped cams 24, 25, 26, adapted to engage in a depression of a correspondingly shaped contact spring 27. The body 5 is provided with a pinion 28 meshing with a toothed wheel 29, which is rotatably mounted on a pin 30 and formed integral with a ratchet wheel 31. The control lever 32 is also mounted on the pin 30 and formed with an extension 33 on which a pawl 34 is mounted which falls into the ratchet wheel 31 by its own weight. The control lever 32 is acted upon, against the control pressure exerted by the knee of the seamstress, by a spring 35 which is suspended from a lug 36 of the extended control lever 32 and secured on a projection 37 in the part 38 of the casing by means of a screw 39. The part 1 of the casing is secured to the part 38 thereof by screws 40, 41, 42.

The operation is as follows:

In Figs. 1 to 7 the control lever 32 is shown in the position A which corresponds to the zero position of the controller cylinder. The cycle of switching operations comprises four positions hereinafter referred to as position A, B, C, D. The end position E ensures the correct position of the ratchet wheel 31 for the beginning of a new cycle. In the position shown in Figs. 1 to 7 the current carrying springs 22, 23, 27 engage over the cam 18 corresponding to the zero position. The control device 44 is connected if the current carrying springs 22, 23 are short-circuited. The electro magnet 45 is connected when the current carrying springs 23, 27 are short-circuited and effects changing over of the feed of the sewing machine from "forward" to "reverse."

If the control lever 32 is moved into the position B by the knee, the controller cylinder is rotated through the ratchet wheel 31 and the pinions 29, 28, until the springs 22, 23 engage over the contact bar 12, Fig. 8. The current carrying spring 27 slides on the slideway 43 of the insulating body 5. The springs 22, 23 forming contacts are short-circuited by the contact pin 12, so that the control device is started and the sewing machine is driven at a predetermined low number of stitches, so that it is possible to sew forward, as long as the contact device remains in the position B (see Fig. 8). Now, if the controller cylinder is turned into the position C, the current carrying springs 22, 23 engage over the insulating cam 19 (see Fig. 9), so that the supply of current to the control device is interrupted and the needle or the needle bar is automatically moved into a desired dead-centre

position, e. g. the upper dead-centre position. During these operations the current carrying contact 27 remains on the slideway 43.

If the controller cylinder is rotated into the position D, the current carrying springs 22, 23, 27 will engage over the contact pin 13, Fig. 10. In this case both the circuit for the control device and the circuit for the electromagnet 45 is closed, with the result that the sewing machine will continue to run at a speed corresponding to a predetermined number of stitches. The feed is changed over to "reverse" under action of the electromagnet 45, so that in this position any number of stitches can be sewn in the reverse direction until the control lever is moved into the position E. In position E all of the three contacts engage over the insulating cam 20 and all of the circuits are interrupted, Fig. 11. Here again the needle bar will take up a desired dead-centre position, for example, the upper one. In the position E the ratchet wheel 31 reaches a position which renders it possible that the pawl 34 can engage the next tooth, since the positions A-D are within one pitch unit of the ratchet wheel. The controller cylinder accordingly is practically again in its zero position and the said cycle of operations can be repeated any number of times through the contact pin 14, the insulating cam 21, contact pin 15, insulating cam 16 etc.

In order to have the possibility, independently of the said contact device, of changing the feed to "reverse" by a corresponding adjustment of the electromagnet 45, according to the invention a switch 46 is provided. If said switch 46, Figs. 7, 12 and 13 is operated, for instance, by manual or by pedal pressure or by Bowden control, the circuit for the electromagnet is closed, independently of the actual position of the controller cylinder. However, it is also possible to change the direction of speed mechanically, e. g. by a knee lever, by Bowden control or by similar means.

Fig. 12 illustrates a sewing machine embodying the present invention and comprising a superstructure 50 having a flywheel 51 and a grooved pulley 52 mounted on a drive shaft 53. Drive shaft 53 is rotatably attached to superstructure 50 and is actuated by an electric motor 54 through a grooved pulley 55 and a pulley belt 56. Motor 54 is controlled by a clutch 57 which is actuated by a lever 58 pivotally connected by a pull rod 59 to a foot pedal 60. Pedal 60 is mounted so that it can be tilted sideways as well as turned about trunnions 61 and 62 in the known manner to bring to rest the needle in the upper or lower dead-center position.

The control device 44 is connected to shaft 53 by a suitable grooved pulley 63 and imparts by an auxiliary drive mechanism therein when motor 54 is disconnected from shaft 55 a speed lower than that derived from the normal main drive motor 54. Device 44 is controlled by the contact device disclosed and housed in casing or frame 1. Device 44 further controls and effects the reverse sewing by controlling the circuits which energized the electromagnet 45.

The electromagnet 45 is mounted on the superstructure 50 (as shown in Fig. 12) and acts vertically on the stitch setting screw 65. As shown in Figs. 13 and 14 the neck of screw 65 is embraced by a collet 66 held together by a pin 67. The pin is secured in an elongated slot 68 in an actuating fork 69 of the electromagnet 45 or of a pull rod 70. The actual reversing movement of the stitch setting screw is well known in the art and will not be needed herein to fully understand the invention claimed.

While the invention has been described in detail with respect to a now preferred example and embodiment of the invention it will be understood by those skilled in the art after understanding the invention that various changes and modifications may be made without departing from the spirit and scope of the invention and it is

intended, therefore, to cover all such changes and modifications in the appended claims.

I claim:

1. In an electrically operated and electromagnetically controlled sewing machine employing a main drive member operable at a predetermined speed the combination comprising an auxiliary drive member for actuating said machine at a reduced speed, a stitch setting means for changing said machine over between forward and reverse sewing of said machine, an electromagnet for actuating said stitch setting means when energized to effect changes in sewing direction of said machine, a control device adapted to actuate said auxiliary drive member and switching means for correlating the action of said control device and said electromagnet comprising a lever operable by an operator, means connected to said lever to actuate said switching means in only one direction to selectively energize and deenergize said control device and said electromagnet in a given cycle of operation.

2. In an electrically operated and electromagnetically controlled sewing machine employing a main drive member operable at a predetermined speed the combination comprising an auxiliary drive member for actuating said machine at a reduced speed, a stitch setting means for changing said machine over between forward and reverse sewing of said machine, an electromagnet for actuating said stitch setting means when energized to effect changes in sewing direction of said machine, an electric control device adapted to actuate said auxiliary drive member, switching means for correlating the action of said control device and said electromagnet comprising an insulating contact drum, a plurality of spaced contacts arranged on the circumference of said drum, electric circuits connecting said contacts to a source of electrical energy, spring contacts cooperating with said contacts arranged on the circumference of said drum and electrically connected to said control device and said electromagnet, and means actuatable by an operator to actuate said drum to selectively energize and deenergize said control device and said electromagnet in a given cycle of operation.

3. In an electrically operated and electromagnetically controlled sewing machine employing a main drive member operable at a predetermined speed the combination comprising an auxiliary drive member for actuating said machine at a reduced speed, a stitch setting means for changing said machine over between forward and reverse sewing of said machine, an electromagnet for actuating said stitch setting means when energized to effect changes in sewing direction of said machine, an electric control device adapted to actuate said auxiliary drive member, switching means for correlating the action of said control device and said electromagnet comprising an insulating contact drum, a plurality of spaced contacts arranged on the circumference of said drum, electric circuits connecting said contacts to a source of electrical energy, spring contacts cooperating with said contacts arranged on the circumference of said drum and electrically connected to said control device and said electromagnet, a lever operable by the knee of an operator, and a pawl mechanism connecting said lever with said drum to actuate said drum in only one direction to selectively energize and deenergize said control device and said electromagnet in a given cycle of operation.

4. An electrically operated and electromagnetically controlled sewing machine in accordance with claim 3 wherein the pawl mechanism is connected to said drum by means of a gear ratio transmission.

5. An electrically operated and electromagnetically

controlled sewing machine in accordance with claim 3 wherein the operation of said lever is effected against the action of a spring.

6. An electrically operated and electromagnetically controlled sewing machine in accordance with claim 3 wherein the pawl mechanism is connected to said drum by means of a gear ratio transmission the tooth distribution of the gears being arranged so that the pawl of the knee lever engages the next tooth of the gear transmission after a predetermined movement of said lever.

7. In an electrically operated and electromagnetically controlled sewing machine employing a main drive member operable at a predetermined speed the combination comprising an auxiliary drive member for actuating said machine at a reduced speed, a stitch setting means for changing said machine over between forward and reverse sewing of said machine, an electromagnet for actuating said stitch setting means when energized to effect changes in sewing direction of said machine, an electric control device adapted to actuate said auxiliary drive member, switching means for correlating the actions of said control device and said electromagnet comprising an insulating contact drum having indentations extending axially thereof and rib-shaped projections arranged between said indentations and serving as rest cams, contact bars arranged within said indentations some of which are electrically connected to said control device and others of which are electrically connected to said electromagnet, spring contacts arranged to selectively engage said contact bars and said rest cams, electric circuits connecting said spring contacts to a source of electrical energy, said spring contacts upon actuation of said drum selectively energizing and deenergizing said control device and said electromagnet, and means operable by an operator to rotate said drum in only one direction a predetermined distance to selectively energize and deenergize said control device and said electromagnet in a given cycle of operation.

8. In an electrically operated and electromagnetically controlled sewing machine employing a main drive member operable at a predetermined speed the combination comprising an auxiliary drive member for actuating said machine at a reduced speed, a stitch setting means for changing said machine over between forward and reverse sewing of said machine, an electromagnet for actuating said stitch setting means when energized to effect changes in sewing direction of said machine, a control device adapted to actuate said auxiliary drive member, switching means for correlating the action of said control device and said electromagnet comprising a lever operable by an operator, means connected to said lever to actuate said switching means in only one direction to selectively energize and deenergize said control device and said electromagnet in a given cycle of operation, and means comprising a switch connected to a source of electrical energy for energizing and deenergizing the electromagnet for the purpose of changing the direction of sewing of said machine independently of the particular position of said switching means.
